L. REICHOLD

ELECTRIC HEATING DEVICE

Filed August 13, 1925

UNITED STATES PATENT OFFICE.

LUDWIG REICHOLD, OF WINSTED, CONNECTICUT, ASSIGNOR TO THE FITZGERALD MANUFACTURING COMPANY, OF WINSTED, CONNECTICUT, A CORPORATION OF CONNECTICUT.

ELECTRIC HEATING DEVICE.

Application filed August 13, 1925. Serial No. 49,990.

This invention relates to improvements in electric heating devices, and more particularly to such plates of the hot plate type for domestic use.

It has heretofore been sought to construct electric heating devices which may have the heating element brought into close proximity to the surface to be heated, and in which the resistance wires are protected and insulated in a satisfactory manner. The great difficulty of the previous constructions has been the fact that the heating element wires were not brought into sufficiently close proximity with the plate to be heated, but were held at a distance therefrom, and in particular were subject to physical deterioration by abrasion. Furthermore, in such devices it was difficult to maintain the proper plane relation of the heating element wires with regard to the plate to be heated.

According to the present invention, a very simple and cheaply constructed assembly is provided which may be easily assembled and dismounted at need, and yet which presents the heating element wires in close and positive relation with regard to the plate.

One form of execution of such a structure is shown on the accompanying drawings, in which:

30 Fig. 1 is an elevation of a waffle iron employing heating elements according to the present invention.

Fig. 2 is a longitudinal section of the device substantially on line 2—2 of Fig. 3, but 35 showing the other parts in position.

Fig. 3 is a plan of the base plate, with the heating element wire in position thereon.

This electric heating device has the hot plate section proper with waffle iron studs 40 thereon at one face, and on the other face a stud 2 with a threaded bolt 3 extending therefrom, the stud being arranged substantially at the center of the plate and projecting at right angles therefrom.

45 A disk of mica 4 has a central aperture which closely fits the stud 2, and is received tightly against the surface of the plate 1. This disk serves both as electrical and mechanical protection for the heating element.

50 The heating element assembly has the base plate 5 of relatively thick metal. It is of substantially circular form, with a central aperture 6 therein to adapt it to be placed over and around the stud 2. A flattened

or chordally cut-away portion 7 exists at 55 one part thereof, and diametrically opposite it a corresponding cut-away portion 8; which, furthermore, has a cut-away section 9 extending inwardly therefrom. A sheet of asbestos 10 is mounted on the face of this 60 plate 5 and conforms substantially to its shape. A series of disks 11 of asbestos board are mounted on top of this asbestos sheet 10, and are held spaced therefrom by smaller disks 12 of similar material. The preferred 65 method of mounting these double washer assemblies is by providing a small hole in the plate 5 at the point where they are to be located; a hollow rivet 11^a is then passed through the plate 5, the asbestos sheet 10, and 70 the disks 11 and 12, and clinched in position, thus holding the members firmly and fixedly assembled to form a unitary and rigid whole.

The terminal bolts 13 and 14 for the heating element wires are mounted upon the sheet of mica 15, and are separated from the plate 5 by a series of mica washers 16 which are received in two holes 17 formed in the plate 5, as may be seen from Fig. 2. 75 These mica washers are substantially the same diameter of the holes and when the bolts are drawn tight they, by their natural irregularity of outline in the usual process of manufacture, are held in frictional and 80 overlapping relation with regard to each other and to the plate, so that the terminal bolts are fixed in position. In addition to this method of holding the terminal bolts 85 13 and 14 in place, the mica sheet 15 projects under the asbestos sheet 10, and is held thereby as well as by the rigidity of the heating element wire itself. In practice it has been found that a very rigid assembly 90 may thus be made.

95 The heating element wire 20 is of asbestos-covered type and of a suitable resistive material. The terminal clips 21 are provided at the ends for reception upon the terminal bolts 13, 14. This heating element wire 20 100 passes successively in zigzag fashion from one terminal, around the series of washers 11, 12, to the other terminal, as shown in Fig. 3. The heating element wire 20 is held in fixed relation to the plate 5 by the washers 11 which project slightly over it, as shown in Fig. 2.

When this plate 5 with the asbestos sheet

10 and the heating element wire mounted fixedly thereon is placed in contact with the mica sheet 4, the heating element wire is brought into very close proximity with 5 the hot plate 1 proper and is separated therefrom merely by the mica-protecting sheet.

In order to prevent a buckling or warping of the plate 5 under heat and pressure, it is preferred to support the latter intermediate 10 its center and edge. This is accomplished by a spherical dome-shaped cup 25 which has a central hole 26 to enable it to fit over and around the threaded bolt 3. A nut 27 is employed to force the dome into contact 15 with the plate 5, as shown in Fig. 1. It will be noted that the edge 28 of this dome-shaped cup 25 engages the plate intermediate the central aperture 6, and the outer edge of the same.

20 This device has been shown and described as being applied to a waffle iron, but it will be understood that it is of far wider application. In the particular form illustrated in Fig. 2 the rear side of the element is shown 25 as covered and protected by a cap 30 which fits the rebated edge 31 of the plate 1, and is held in fixed relation to the other elements by a nut 32 on the threaded bolt 3. The plate may have the hinging lug 34 formed 30 integrally therewith; so that two such elements may be assembled, as shown in Fig. 1, and mounted upon a suitable standard 35 with base 36. The lower element A is fastened to the standard 35, while the upper element 35 is hinged to the lower at C and has the lifting handle D for easy and safe operation.

Obviously, modifications may be made 40 from the particular embodiment represented within the scope of the appended claims.

I claim:

1. In an electric heating device, a heating element assembly consisting of a rigid metal base plate, an insulating sheet upon said 45 base plate, insulating spacing and holding washers on said insulating sheet, metal rivets

passing through said plate, said sheet, and said washers to fixedly connect the same, terminal bolts secured to and insulated from said base plate, and a heating element passing from one terminal bolt to another in zigzag manner around said washers and held by said bolts and washers in fixed relation to said base plate.

2. In an electric heating device, a heating element assembly having a base plate with apertures therein, an insulating sheet on one side of said base plate, a terminal bolt passing through said sheet and one of the apertures, and mica washers substantially of the size of the aperture and disposed about said bolt and in said aperture and extending beyond the same, whereby said bolt upon being drawn tight clamps said washers into locking engagement with the 60 said base plate and prevents movement of said bolt with regard to said plate.

3. In an electric heating device, a heating plate, a clamping bolt extending from said heating plate, a mica sheet loosely located upon said plate and around said bolt; a heating element assembly consisting of a base plate, an insulating sheet on said plate, spacing and holding washers on said sheet, rivets passing through said plate, said sheet and said washers to fixedly connect the same, an insulating terminal sheet on said plate, terminal bolts mounted on said terminal sheet, and a heating element passing from one terminal bolt to another 75 in zigzag manner around said washers; a spherical dome-shaped cup having an aperture for said clamping bolt and engaging said base plate intermediate the center and the edge, a nut on said bolt to clamp said heating element assembly into close and fixed relation with said heating plate, and a protecting cap inclosing the heating element assembly.

In testimony whereof, I affix my signature.

LUDWIG REICHOLD.
